Filed July 30, 1973, Ser. No. 383,686

Term of patent 14 years

Int. Cl. D12—16

U.S. Cl. D12—156

FIG. 1

FIG. 2

FIG. 3

FIG. 1 is a side elevational view of an auxiliary housing for use with pickup trucks showing my new design, it being understood that the opposite side is a mirror image thereof, the broken line showing the pickup truck being for illustration purposes only;

FIG. 2 is a front elevational view thereof;

FIG. 3 is a top plan view thereof;

FIG. 4 is a bottom plan view thereof;

FIG. 5 is a rear elevational view thereof; and

FIG. 6 is a rear elevational view of an auxiliary housing for use with pickup trucks showing a second embodiment of my new design, it being understood that the sole difference resides in the configuration of the rear.

The fragmentary crisscross pattern shown on the forward projecting portion of the auxiliary housing in FIGS. 1, 2, 3 and 4 is understood to be continuous throughout the areas indicated.

I claim:

The ornamental design for auxiliary housing for use with pickup trucks, substantially as shown and described.
